UNITED STATES PATENT OFFICE.

SAMUEL N. GOODMAN, OF PHILADELPHIA, PENNSYLVANIA, ASSIGNOR TO
CONYERS BUTTON AND MARTIN L. FINCKEL, OF SAME PLACE.

DESIGN FOR A KNITTED FABRIC.

SPECIFICATION forming part of Design No. 18,674, dated October 9, 1888.

Application filed August 13, 1888. Serial No. 282,650. Term of patent 3½ years.

To all whom it may concern:

Be it known that I, SAMUEL N. GOODMAN, a citizen of the United States, and a resident of Philadelphia, Pennsylvania, have invented a new and original Design for a Knitted Fabric, of which the following is a specification.

My design is fully shown in the accompanying drawing.

The design comprises a backing composed of parallel bands *a* and a face consisting of the zigzag ribs *b*, the bars of each rib crossing first at one angle and then at a reverse angle from band to band of the backing, and the ribs being substantially parallel with each other. Each

bar of each rib has at or about its center a prominent spot, *d*, of a color different from that of the rib.

I claim—

The design for a knitted fabric, substantially as described, and as shown in the accompanying drawing.

In testimony whereof I have signed my name to this specification in the presence of two subscribing witnesses.

SAMUEL N. GOODMAN.

Witnesses:

WILLIAM D. CONNER,
HARRY SMITH.
